(57) **CLAIM**

I claim the ornamental design for an insulated food container, as shown and described.

DESCRIPTION

FIG. 1 is a left side perspective view of the insulated food container in a closed configuration.

FIG. 2 is a left side elevation view thereof.

FIG. 3 is a front elevation view thereof.

FIG. 4 is a top plan view thereof.

FIG. 5 is a right side elevation view thereof.

FIG. 6 is a back elevation view thereof.

FIG. 7 is a bottom plan view thereof.

FIG. 8 is a bottom, back, and left perspective view thereof.

FIG. 9 is a left side perspective view thereof, showing only the top half of the container.

FIG. 10 is a left side elevation view thereof.

FIG. 11 is a front elevation view thereof.

FIG. 12 is a top plan view thereof.

FIG. 13 is a right side elevation view thereof.

FIG. 14 is a back elevation view thereof.

FIG. 15 is a bottom plan view thereof.

FIG. 16 is a bottom and left side perspective view thereof.

FIG. 17 is a left side perspective view thereof, showing only the bottom half of the container.

FIG. 18 is a left side elevation view thereof.

FIG. 19 is a front elevation view of the thereof.

FIG. 20 is a top plan view thereof.

FIG. 21 is a right side elevation view thereof.

FIG. 22 is a back elevation view thereof.

FIG. 23 is a bottom plan view thereof; and,

FIG. 24 is a bottom perspective view thereof.

The top and bottom halves of the container are shown independently in FIGS. 9-16 and FIGS. 17-24 for convenience of illustration only.

1 Claim, 9 Drawing Sheets
